(57) **CLAIM**

The ornamental design for a vehicle side fairing as shown and described.

DESCRIPTION

FIG. 1 depicts a front, left, top perspective view of a vehicle side fairing showing our new design.

FIG. 2 depicts a front, right and bottom perspective view thereof;

FIG. 3 depicts a front view thereof;

FIG. 4 depicts a back view thereof;

FIG. 5 depicts a left side view thereof;

FIG. 6 depicts a right side view thereof;

FIG. 7 depicts a top view thereof; and,

FIG. 8 depicts a bottom view thereof.

The ghosted or low contrasted portions of the vehicle side fairing illustrate portions that form no part of the claimed design. The dash lines depict boundaries of the claimed design.

1 Claim, 6 Drawing Sheets
